REINFORCED HANDLE

Filed May 15, 1926

Inventor,

clifford D. Upton,
By F. K. Gasset,

Attorney.

UNITED STATES PATENT OFFICE.

CLIFFORD D. UPTON, OF PIQUA, OHIO, ASSIGNEE TO THE WOOD SHOVEL AND TOOL COMPANY, OF PIQUA, OHIO, A CORPORATION OF OHIO.

REINFORCED HANDLE.

Application filed May 15, 1926. Serial No. 109,250.

This invention relates to wooden handles for shovels, rakes, hoes and the like; in fact handles for all purposes wherein the handle is long, straight and of comparatively small 5 diameter.

One of the objects of my invention is to reinforce a handle and enable it to withstand excessive strains, especially strains applied in certain directions, as, for example, 10 bending strains put upon the handle of a shovel when the shovel is used as a pry. Another object is to permit the use of lumber in making handles which could not otherwise be used for the purpose. Another 15 object is to prevent warpage of handles.

In the succeeding specification I shall first describe the structure of my improved handle and I shall then describe one of its uses. In the accompanying drawing, which 20 forms part of the specification,

Fig. 1 shows two strips of wood which are to be joined to form a handle;

Fig. 2 shows an end view of a handle made of two such strips of wood, the strips when 25 first joined forming a square cross-section, indicated by dotted lines, which is then turned to the circular cross-section shown in full lines;

Figs. 3 and 4 show two forms of a metallic connector by which the two parts of the 30 handle are united;

Fig. 5 shows a shovel equipped with a handle embodying my invention;

Fig. 6 shows a shovel handle alone, from 35 a point of view ninety degrees around from that seen in Fig. 5;

Fig. 7 shows in an enlarged view the manner of securing the upper ends of the shovel straps to the handle, whereby the usual rivet 40 at this point is dispensed with;

Fig. 8 shows a cross-section through the handle on line 8—8 in Fig. 5, and

Fig. 9 is a sectional view of a modified form of metallic connector.

Referring first to Fig. 4, it is seen that 45 the connector comprises a strip of metal 10, both edges having been notched, as at 11, leaving a series of projections 12, which, for lack of a better term, I shall call blades. 50 These blades are bent to positions less than ninety degrees from the strip 10, alternate blades being bent toward one side of the strip and the intervening blades bent to a similar position with reference to the other 55 side of the strip. The blades situated oppo-

site each other on the strip 10 are bent in opposite directions, but there is no particular merit in this arrangement, as these opposing blades might as well be bent toward the same side of the strip. The strip shown in Fig. 60 3 differs from that shown in Fig. 4 only in that its blades 12 are not separated by notches 11. The edges of the strip 10 are merely clipped and the resulting blades bent in alternate directions as before. 65

Each of the wooden strips 15, in Fig. 1, being alike I shall describe one only. Preferably the strip is twice as wide as it is thick, and on one side it is channeled, as at 16, to a depth equal to one-half the thickness 70 of the body 10 of the connector. At each edge of this shallow channel a deep, narrow, slot 17 is cut, to receive the blades 12 on one side of the connector. These slots are inclined to an angle corresponding to the 75 inclination of the blades. When the strips are united by the connector the faces 18—18 of the strips come together as is seen in Fig. 2. The preferred method of assembling the parts is to place the two wooden strips face 80 to face and then slide the connector into its place between them. Before putting the wooden strips together the faces 18—18 may be coated with glue, preferably water-proof glue. This assemblage may then be turned 85 or otherwise reduced to the circular cross-section shown in Fig. 3. It is possible, of course, to give the strips 15 their semi-cylindrical form before they are assembled.

There are two advantages in making the 90 connector as in Fig. 4, that is with the notches 11 between the blades. First, it reduces the weight of the reinforcement. Second, the spaces between the blades afford an opportunity for a slight flexure of the body 95 10 as the connector is forced into place between wooden strips, which, if the metal has a reasonable amount of resiliency, will enable the connector to draw the strips tightly together. To take advantage of this it is 100 necessary to make the depth of the channels 16 such that this flexure can take place. But a very slight difference in this respect is sufficient as the flexure need not be great. It is not necessary to use metal as thick as 105 indicated by the drawing, this however, being a mere question of designing, and depending on the uses to which the handle will be put. Nor is the use of my method of joining wood limited to handles; it is ap- 110

plicable to any case where it is desirable either to make a very strong joint or to reinforce wood.

While I have referred to the members 12 of the connector as blades, it is plain that as a whole the union between the connector and wooden strips is on the principle of the well known dove-tail. The key 19 formed by cutting the slots 17 is dove-tail in form 10 and the blades embrace it like the other member of a dove-tail joint. Because of the extreme intimacy of the connection, the blades being confined in the comparatively close fitting grooves, forming a sort of interlock, the connector stiffens a handle very materially, even against strains perpendicular to the body 10 of the connector. But in the other direction, that is, against strains parallel to the body of the connector, the 20 handle has very great strength and rigidity. When it is desirable to provide substantially equal rigidity in both directions a connector of the form shown in Fig. 9 may be used. This connector has ribs 30 projecting from 25 each side of the body 10, which, aided by the rigidity due to the interlocking of the connector and wood, give the handle substantially equal strength and rigidity in all directions. My method of reenforcing handles is 30 useful in keeping them from warping, which is a valuable function where handles are much subjected to the action of water. My invention is also applicable to other uses than shovel handles. For example, it is applicable to the wooden bars or "doctors" used 35 for smoothing the color after it is applied to the fabric in machines for making oil-cloth. In such machines much trouble is experienced from warping of the bars because of their being wet so much of the time, and also because of their being alternately 40 wet and dry. Instead of providing the ribs 30, the body 10 may be provided with longitudinal corrugations to give it stiffness. 45 This is so obvious that it is deemed unnecessary to illustrate it.

In Fig. 5 I show a shovel equipped with a handle embodying my invention. The metal part of the shovel is of the usual style, the 50 blade 25 having the usual pocket, comprising straps 26 and 27, for attaching the wooden handle to the blade. This handle is reenforced for a portion of its length with a metallic connector 28, which is indicated diagrammatically with dotted lines. The handle must be bent in the usual way to get it 55 into the pocket, and to permit this the connector or reenforcement stops short of the bend. But it extends sufficiently past the 60 ends of the straps to transfer all strain to the straps, therefore leaving no weak point in the handle. Instead of the rivet which ordinarily secures the ends of the straps 26 and 27 to the handle, the straps are bound to 65 the handle by a metal band 29, which is

wrapped around the straps and its ends tucked through a hole in one of the straps. The band is then contracted by a swaging operation. As this specific structure of the handle, including the band for securing the 70 straps is not my invention the foregoing description is sufficient. I merely show it here to demonstrate the reenforcing function of the connector 28. The handle being set in the pocket with the body 10 of the connector 75 perpendicular to the blade, any strain put upon the handle when the shovel is used as a pry is received edgewise by the body of the connector.

In other types of shovels this reenforcement is similarly, or even more effective. For example, shovels for digging holes for telephone poles have handles of various lengths, as much as ten or twelve feet in some cases, and these are subjected to very 80 severe strain at times. Because of this it has been necessary to use very high class lumber in making such handles. With my method of building up and reenforcing handles, not only can smaller pieces be used, but a lower 85 grade of lumber can be used and yet produce stronger handles than before. As lumber suitable for shovel handles and other articles to which my invention may be applied is becoming scarce and therefore expensive, this is an important consideration. 90

It is not to be understood that my invention is limited, in its broader aspects, to the details of construction shown. Its limitations are only such as my claims impose. 100

What I claim as my invention is as follows:

1. As an article of manufacture, two strips of wood united by strips of metal lying partly in one strip of wood and partly in 105 the other in longitudinally disposed grooves formed in the wood, and inclined with reference to the abutting surfaces of the wooden strips and with reference to each other, whereby the union is effected on the principle of a dove-tail joint. 110

2. A handle or the like comprising two strips of wood, each having two slots cut in one side parallel to each other and to the grain of the wood, said slots converging from 115 the surface inward, thereby forming an intermediate key of dovetail cross-section; and a metallic connector comprising a flat body having two rows of blades projecting from each side in converging relationship, 120 thereby forming on each side of said body a channel complementary to and adapted to receive the key of one of said strips.

3. A handle or the like comprising two strips of wood, each having two slots cut in one side, parallel to each other and to the grain of the wood, said slots converging from the surface inward, forming an intermediate key of dovetail cross-section; and a metallic connector comprising a thin flat body from 125 130

each edge of which blades project toward each side of the body and leaning toward each other to form on each side of the body a channel complementary to and adapted to receive one of said keys, said keys being reduced in height with reference to the adjacent surfaces of the strips, thereby providing a space for the body of the connector and enabling said adjacent surfaces to contact, thus entirely enclosing the connector in the wood.

4. A handle composed of wood with a broad and relatively thin metallic reenforcement embedded within and completely surrounded by the wood.

5. A handle composed of two strips of wood having a metal reenforcement between them, which reenforcement is interlocked with said strips of wood at points intermediate its extremities.

6. A handle composed of two strips of wood with a metal reenforcement confined between them, portions of the wood coming together face to face on each side of said reenforcement, which portions are united with glue, said reenforcement being interlocked with said strips at points intermediate its extremities.

7. An article of manufacture composed of two strips of wood united face to face by metal connectors, comprising flat blades radiating in two directions from and integral with a common body, said blades fitting in slots cut longitudinally in each of the strips at an inclination to said faces, the slots in a given strip inclining in opposite directions.

8. An article of manufacture composed of two strips of wood united by connectors comprising flat blades lying in slots in the strips, said slots being inclined with reference to the surfaces of the strips, the inclination of

one slot in a strip being different from that of the other slot.

9. As an article of manufacture, a wooden handle composed of two halves placed face to face, each half having two deep, narrow, longitudinally extending slots, said slots being at an angle to each other in cross-section, and a metal connecting device having blades adapted to slide into said slots and hold the parts together.

10. As an article of manufacture, a handle composed of two strips of wood, each having two deep, narrow, longitudinally extending slots cut in one side, said slots inclining with reference to the surface in which they are cut and in opposite directions with reference to each other; and means for uniting said strips, comprising a strip of metal having blades attached to each edge and extending alternately from each side of the strip at inclinations corresponding to that of the slots in said strip, said blades being slid into the slots and thereby uniting the wood strips to said metal strip.

11. A handle or the like comprising two strips of wood, each having two slots cut in one side parallel to each other and to the grain of the wood, said slots converging from the surface inward, thereby forming an intermediate key of dovetail cross-section; and a metallic connector comprising a flat body having two rows of blades projecting from each side in converging relationship, thereby forming on each side of said body a channel complementary to and adapted to receive the key of one of said strips, said body having a longitudinal rib extending from each side to give the connector rigidity perpendicular to said body.
